UNITED STATES PATENT OFFICE.

BENJAMIN R. HAWLEY, OF CHICAGO, ILLINOIS, ASSIGNOR TO AGNES HAWLEY, OF SAME PLACE.

WHEAT-HEATER.

SPECIFICATION forming part of Letters Patent No. 247,640, dated September 27, 1881.

Application filed July 18, 1881. (No model.)

To all whom it may concern:

Be it known that I, BENJAMIN R. HAWLEY, of Chicago, Cook county, State of Illinois, have invented certain new and useful Improvements 5 in Wheat-Heaters, of which the following is a specification.

This invention relates to the manner of heating wheat-heaters, and also to the construction of the heater itself, and will be understood 10 from the drawings and the description given below.

Figure 1 shows a section of a wheat-heater and the heating apparatus used therewith constructed according to my present invention. Fig. 2 shows a similar view of a modified form of the apparatus. Figs. 3 and 4 are horizontal sections of the wheat-heater proper upon lines *x x* and *y y*, respectively.

Wheat-heaters have usually been warmed, 20 so far as my information goes, by steam or hot water passing through coils or passages in the heater when the milling machinery is operated by steam. This, perhaps, is as good and cheap a method as has been devised; but where steam 25 is not employed for other purposes it necessitates expensive apparatus and a needless consumption of fuel.

My invention is equally effective, and can be placed in any mill at very small cost, and 30 be operated much more cheaply than the other.

In said drawings, *A* represents a stove, which may be of any ordinary construction, and of such dimensions as are requisite for the 35 number of heaters to be warmed by it. It is surrounded by a non-conducting case, *A'*, with an air-space, *A²*, intervening upon all sides. The smoke passes out, as usual, through a pipe, *A³*. From the top of the air-space *A²* are 40 passages *B*, leading upward into the wheat-heaters *C*, and opening thereinto at such a point as will insure the discharge of the hot air to the top of the heater. The warm air is thus conducted to the interior of the heater, and it circulates through the same and around the 45 tapering pipes *e*, through which the wheat is fed, thereby warming the wheat to the proper degree. After circulating through the heater the air falls as it cools through the pipe *D*, opening from the bottom of the heater and

leading to the bottom of the air-space *A²*, where 50 it is rewarmed and again sent up to the wheat, thus traveling round and round continuously through said air-space, the passages *B*, wheat-heater *C*, and return-pipes *D*. The wheat slowly descends through the flues *e*, and issues thence into the conductor *E*, by which it 55 is carried to the burrs.

In the modified form shown in Fig. 2 the stove is utilized for heating a part of the mill, and the smoke is conducted into and through 60 a drum, *F*, which is warmed thereby. Through this drum are air-flues *f*, affording passage to the continuously-circulating air, which traverses similar up-air pipes *B* and return-pipes *D* between the drum and heater. The latter 65 may be similar to the heaters already described, or it may be less complex in construction, with fewer grain-passages, as shown in the drawings. The pipes *B* and *D* open from the top and into the bottom of the drum, respectively, 70 in the same manner as they lead from and into the air-space *A²* in the other form of the invention.

This apparatus is not only much less costly to construct, but it lasts much longer than the 75 steam, does not endanger the wheat through wetting by leaks, will not get out of order, and can be heated up in much less time than the old apparatus.

In the drawings I have used arrows to indicate the movement of the air and grain currents—viz., those with circles upon the shafts to indicate smoke, the unfeathered ones for the warm rising air, and feathered ones with *X* on the shaft for the cooled falling air, and the 85 plain feathered ones for the grain.

As drying of the berry is not desired, there is no communication between the interior of the grain-flues and the air-space surrounding them, so that the hot air is excluded from contact. 90

I claim—

1. The grain-heating apparatus described, consisting of a heater having flues through it open to the descending grain, an air-space surrounding such flues, but not communicating therewith, a conductor for carrying off the grain, a stove for warming the air, an air-cham- 95

ber surrounding the stove, pipes adapted to conduct the air from said air-chamber to the air-space in the heater, and other pipes to return it from thence to the air-chamber, substantially as and for the purpose set forth.

5. 2. The grain-heater wherein are combined the pipes 'c', running through the heater and forming passages for the grain, an air-space surrounding said grain-passages, but having

no communication therewith; a conduit, B, for discharging the warm air to the top of said space, and a conduit, D, to draw off the air from the bottom of the same, substantially as and for the purpose specified.

B. R. HAWLEY.
